UNITED STATES PATENT OFFICE

ARTHUR E. RANSOME, OF GLENCOE, AND EMIL M. SCHMIDT, OF CHICAGO, ILLINOIS

DESIGN FOR A FINGER RING OR SIMILAR ARTICLE

Application filed March 9, 1929. Serial No. 30,416. Term of patent 3½ years.

To all whom it may concern:

Be it known that we, ARTHUR E. RANSOME, residing at Glencoe, Cook County, Illinois, and EMIL M. SCHMIDT, residing at Chicago, Illinois, both citizens of the United States, have jointly invented a new, original, and ornamental Design for Finger Rings and Similar Articles, of which the following is a specification, reference being had to the accompanying drawings, forming part thereof.

We claim:

The ornamental design for a finger ring or similar article, substantially as shown.

ARTHUR E. RANSOME.
EMIL M. SCHMIDT.
